Attorney

United States Patent Office.

JOHN T. ELLIOTT, OF GRAND RAPIDS, MICHIGAN.

Letters Patent No. 61,817, dated February 5, 1867.

IMPROVED CLOTHES-DRYER.

The Schedule referred to in these Letters Patent and making part of the same.

TO ALL WHOM IT MAY CONCERN:

Be it known that I, JOHN T. ELLIOTT, of Grand Rapids, in the county of Kent, and State of Michigan, have invented new and useful improvements in "Clothes-Dryers;" and I do hereby declare that the following is a full, clear, and exact description thereof, which will enable others skilled in the art to make and use the same, reference being had to the accompanying drawings, forming part of this specification, in which—

Figure 1 is a plan or top view of the clothes-dryer; and

Figure 2 a side elevation of the same.

Similar letters of reference indicate like parts.

The present invention relates to that class of clothes-dryers having the frame to which the clothes are suspended, through lines run around the same, hung upon a centre-post, so as to be revolved; and it consists principally in so hanging or securing the arms of such frame to its common centre head-piece that, when desired, said arms can be swung up and into a vertical position, and thus into a compact shape for being transported or carried, whereby, in case of sudden storms, the clothes-frame, with the clothes suspended to it, can be more readily carried to any suitable place of shelter from the storm.

A, in the drawings, represents the centre-post or upright, having hung upon its upper end the clothes-drying frame B, which consists of a series of radiating arms, C, from a common centre head-piece or block, D; these arms being each hung at E to the sides of the projecting arms F of the head-block, so as to be susceptible of being swung thereon, either into a vertical or horizontal position; they being secured in the latter position by means of pins, a, passed through their inner ends into the head-arms F. The clothes-drying frame is hung in a manner to the post so as to be susceptible of being tilted or inclined in position at pleasure, but as this forms no part of the present invention I do not deem it necessary to herein particularly explain it.

From the above description of the manner in which the several arms of the clothes-dryer frame are suspended to their common centre head-piece or block, it is plain to be seen that, while they can be secured in a horizontal position, they are susceptible of being swung up into a vertical position, or, in other words, closed upon each other, or nearly so, and thus the frame put into a more compact shape for being carried or transported, even with the clothes upon the lines, the importance and advantages of which are obvious.

I claim as new, and desire to secure by Letters Patent—

The combination of the arms C, pivoted and adjustable upon the projecting arms F, of the head-block D, mounted on a tilting arm, and operating substantially as described for the purpose specified.

JOHN T. ELLIOTT.
